[57] CLAIM

The ornamental design for a medicinal sponge container, as substantially shown and described.

DESCRIPTION

FIG. 1 is an isometric view of the medicinal sponge container showing my new design;

FIG. 2 is a top plan view thereof;

FIG. 3 is a front view thereof;

FIG. 4 is a left side view thereof;

FIG. 5 is a right side view thereof;

FIG. 6 is a bottom view thereof;

FIG. 7 is an isometric view of a modified form of my design of the medicinal sponge container;

FIG. 8 is a top plan view of my design of FIG. 7;

FIG. 9 is a front view of my design of FIG. 7;

FIG. 10 is a left side view of the design of FIG. 7;

FIG. 11 is a right side view of the design of FIG. 7; and
FIG. 12 is a bottom view of my design of FIG. 7.
